SPINNING-MULE.

989,513.

Specification of Letters Patent. Patented Apr. 11, 1911.

Application filed November 30, 1910. Serial No. 594,837.

To all whom it may concern:

Be it known that we, WILLIAM D. RUNDLETT and HENRY WHITE, both citizens of the United States, and residents of North 5 Andover, county of Essex, State of Massachusetts, have invented an Improvement in Spinning-Mules, of which the following description, in connection with the accompanying drawing, is a specification, like 10 characters on the drawing representing like parts.

This invention relates to spinning mules, and more particularly to the control of the tension-faller after backing off, our invention having for its object the production of 15 novel and more efficient means than those now known to us for controlling the rise of the tension-faller as the inward movement of the carriage begins after backing off, 20 so that any tendency to break the yarn by sudden engagement with the tension-faller is completely obviated. During the outward run of the carriage the winding and tension fallers are locked out of contact 25 with the yarn, but when the direction of rotation of the spindles is reversed during backing off the fallers are unlocked, the winding-faller descending and the tension-faller rising quickly by the action of 30 the usual weights to engage the yarns, and as some of the yarns at this time are often tighter than others they would be very apt to be broken were the tension-faller allowed to engage and put full tension upon the 35 yarns with a more or less violent shock. Various means have been devised to control the rise of the tension-faller at this time and thereby prevent yarn breakage. In one device wedges or inclines are provided to arrest 40 the descent of one or more of the weight stands until the carriage starts on its inward run, and as the backing off unlocks the tension-faller the weights drop until the weight stand or lever rests on the adjacent wedge 45 attached to the floor. Consequently the wire of the tension-faller can rise only to a point determined by the height or position of the wedge. With a chain connection to the faller-shaft each wedge can control only one 50 set of weights, hence for complete control there must be as many wedges as there are stands of weights. The point at which the wire is checked is usually just short of putting strain on the yarn by the weights, in

order to leave some slack in the yarn, but 55 so slight in amount that snarls or kinks are avoided. This arrangement is defective for the following reason: After the carriage has reached the extreme of its outward movement, usually there still remains some 60 twist to be put into the yarn, known technically as "head twist," and during the addition of this head twist the carriage is moved inward very slowly to compensate for the shortening of the yarn by the twist. Such 65 inward movement, or easing-in, of the carriage varies in extent, depending upon the rapidity and duration of the added twist, consequently the position of the carriage at the moment of backing off is variable. 70 Changes in twist or yarn size, or both, necessitate changes in the position of the wedges to suit such variations in the position of the carriage, and such adjustment of the wedges must be effected manually and at the judgment 75 of the spinner. The lack of uniformity in the adjustment of the several wedges, and the time required to make the change, are very objectionable features of this arrangement, as will be apparent. In yet another controlling device the wedges 80 co-operate with levers each of which is connected by a rigid link to an arm on the tension-faller shaft, and only one of such levers is necessary on each half of the mule, because by reason of the rigid connecting link 85 all of the weights in the vicinity are controlled thereby. This arrangement is preferable as to accuracy and time required for setting, but it also must be manually adjusted to suit the twist or easing-in distance 90 through which the carriage moves, as in the first-mentioned device. Both of these controlling devices are well known and familiar to those skilled in the art, and it will be 95 apparent that in each one the full strain due to the lifting weights is withheld from the yarn until the carriage has moved inward, after backing off, to the point where the arresting wedges fail to act. In both of the 100 foregoing devices, as well as in our present invention, the rising movement of the tension-faller immediately after unlocking and during the greater part of the backing off is controlled by various means, such for instance as shown in United States Patent No. 862,201 granted to one of us August 6, 1907, 105 but in such patent at the end of the back-

ing off the control is completed and the tension-faller is acting to exert full tension upon the yarn, while in the older devices mentioned such control is continued as the carriage begins its inward movement. Consequently the descending winding-faller acting on the yarn, which is slack, and the tension-faller being held stationary by the action of the wedges, results in subjecting the 10 yarn to far less of a jerk than when both fallers are simultaneously in motion in opposite directions and impinging on the yarn at the same moment with their full strain and considerable momentum at the completion 15 of the backing off. Notwithstanding these advantages the objections as to time expended and lack of uniformity in adjusting are always present. In our present invention, however, we have retained the advantages 20 above pointed out due to the use of wedges; but we have eliminated the objectionable features of these older forms of tension-faller control.

In accordance with our invention the 25 means to arrest and control the tension-faller at the completion of the backing off is governed automatically by or through the carriage wheel, the unlocked tension-faller being arrested in its rise at a point which 30 permits it to take up most of the slack yarn resulting from backing off but without exerting any strain thereupon. Thereafter as the carriage moves inward the rotation of the wheel so governs the controlling means 35 as to permit a gradual rise of the tension-faller to finally exert full strain upon the yarn when the said faller is fully released, the gradual descent of the tension-faller thereafter by the pull of the yarn during the 40 winding operation permitting the controlling means to return automatically to normal condition in readiness to act when next called upon. Inasmuch as the fallers are locked until backing off takes place it will 45 be obvious that in our invention the distance traveled by the carriage during easing-in is immaterial, for the upward movement of the tension-faller, when unlocked, to the point requisite to take up the slack yarn produced 50 by backing off sets automatically the controlling means into operative condition, and the subsequent rotation of the carriage wheel as the carriage moves inward governs the subsequent rising movement of the tension-faller. Hence no adjustment whatever is 55 required to compensate for the easing-in, as will appear more clearly hereinafter.

The various novel features of our invention will be fully described in the subjoined 60 specification and particularly pointed out in the following claims.

Figure 1 is a side elevation and part section of a portion of the carriage of a spinning mule, with the winding and tension-fallers, and the draft-rolls, with one em-

bodiment of our present invention shown in connection therewith, the various parts being illustrated in the positions occupied when the carriage is at the end of its inward run; Fig. 2 is a similar view but showing 70 the fallers unlocked and the carriage about to begin its inward run after backing off, the controlling means embodying our invention having full control of the tension-faller; Fig. 3 is a detail view showing certain devices coöperating with the winding and tension-fallers omitted from Figs. 1 and 2 for the sake of clearness; Fig. 4 is an enlarged 75 side elevation of one of the carriage wheels, and the novel tension-faller controlling means 80 in its normal or inactive condition; Fig. 5 is a vertical sectional view of the wheel on the line 5-5, Fig. 4, looking toward the right, but showing the controlling means in elevation; Fig. 6 is a detail, also enlarged, 85 of the controlling means in its active condition and governed by rotation of the carriage wheel, a part of the latter being shown, and it is supposed that said wheel has begun to rotate on the inward run of the carriage; 90 Figs. 7, 8 and 9 are perspective views, on a smaller scale, of different members of the controlling means, to be referred to.

Referring to Figs. 1 and 2 the mule-carriage A, its spindles a; draft-rolls B, Fig. 1; the winding-faller b, its shaft b' and wire b^x; the tension-faller c, its shaft c' and wire c^x; the grooved carriage wheel A' having journals A², the bracket A³ having suitable bearings A⁴ for said journals, and the track 95 C upon which said wheel travels, are and may be in their general features of construction common to spinning mules.

While we have herein shown our novel 100 controlling means governed by one of the carriage wheels, that being quite sufficient in many cases it is to be understood that whenever the size of the mule or other considerations make it necessary or desirable more than one of the controlling means may be 105 employed, and each will be governed by a carriage wheel. In other words the tension-faller controlling means may be multiplied 110 as many times as may be necessary, such duplication being within the spirit and scope 115 of our invention, and hence only one of the controlling means need be described in detail.

Referring to Fig. 3 the arm b² connected 120 with the winding-faller shaft, the strap b^{4x} and attached spring b^{5x}; the arm e rigidly connected with the tension-faller shaft c', and the weight-carrying rod D^x depending 125 from said arm, are all as in the above-mentioned Patent No. 862,201, the downward pull of the weight (not shown) upon the rod D^x effecting the rise of the tension-faller. The jointed links b⁵, b⁷, the former pivoted to arm b² and the latter having a pulley b⁸ 130 for the usual chain b⁹, and the cam D loose

on the winding-faller shaft b' and co-operating with a roll-carrying stud b^e , are also as in said patent, said parts effecting the locking and unlocking of the fallers and being omitted in Figs. 1 and 2 for the sake of clearness in illustration.

In the present embodiment of our invention the carriage wheel A' is provided on one face with an annular locking member shown 10 as a peripheral flange 1, and upon the part 2 of the shaft which provides the journals A^2 we mount loosely the hub 3 of a pawl governor, herein shown as a peripherally grooved segment 4 and illustrated separately 15 in Fig. 7, the segment having a slot 5 therein concentric with its axis. One end of a flexible connector, preferably a chain 6, is attached at 7 to the segment, the connector being led around the grooved face of the segment 20 and thence up to an arm 8 fixedly attached to the tension-faller shaft c' , the arm being curved to clear the winding-faller shaft b' , as shown in Figs. 1 and 2. When the fallers are locked the arm 8 is swung down, as 25 in Fig. 1, slackening the connector 6 so that the segment 4 will by gravity swing down into normal or inactive position below the wheel journals, as in Figs. 1, 4 and 5.

Between the segment and the hub portion a^x 30 of the carriage wheel the hub 9 of a swinging arm 10 constituting a pawl-carrier is loosely mounted on the part 2 of the wheel shaft, the hub 9 having a segmental web-like extension 11 terminating in laterally extended 35 stop lugs 12, 13 which are long enough to engage the top and bottom, respectively of the adjacent part of the bracket A^3 when said pawl-carrier is swung in one or the other direction. The pawl-carrier 10 is thus 40 mounted co-axially with the carriage wheel and the segment and can swing adjacent the latter, the outer end of the pawl-carrier being enlarged to form a hollow boss 14 within and quite near the annular wheel flange 1, 45 the inner end of the boss being recessed at 15.

A locking pawl 16, shown separately in Fig. 9, has a lateral pivot-stud 17 which enters loosely the hollow boss 14, the rounded 50 base of the pawl fitting in the recess 15 and against the adjacent end of the boss, while the toe of said pawl has a wide face 18 to at times engage frictionally the flange 1 and lock the pawl and pawl-carrier to the carriage wheel. Inasmuch as the pawl is at all 55 times between the inner end of the boss 14 and the adjacent face of the wheel rim A^x said pawl is held in proper engagement with the pawl-carrier. A tail 19 extends from the 60 pawl inward toward the axis of the wheel and at its free end has a lateral lug 20 which enters loosely the curved slot 5 of the segment 4, and said lug is always above the pawl-carrier, the weight of the lug and tail 65 being great enough to overbalance the pawl,

when free to act, and to rock the pawl on the pivot 17 far enough to disengage the face 18 from the wheel flange 1. This position of the pawl is shown in Fig. 1 and more clearly in Fig. 4, the fallers at such time being locked, so that the segment 4 hangs down under the wheel axis as far as the connector 6 permits, the lower end of the slot 5 being some distance away from the lug 20, while the pawl-carrier 10 is positioned by engagement of the stop 13 with the under side of the bracket A^3 . 70 75

From the foregoing it will be seen that the pawl is movable bodily with and is supported by the pawl-carrier while it is also 80 movable relatively to the carrier into and out of locking engagement with the carriage wheel.

Starting with the carriage at the inner end of its run, Fig. 1, with the fallers locked and the controlling means for the tension-faller in inactive condition, shown in Figs. 1, 4 and 5, the carriage is moved outward and the yarn is spun or twisted as usual. During such outward run the part 2 of the wheel 85 shaft turns freely in the hubs of the segment and pawl-carrier of the controlling means. At the outer end of the run of the carriage head twist is put into the yarn, and easing-in of the carriage is effected, but 90 with no change in the fallers or the controlling means. Backing off now takes place, the fallers being unlocked and moving in opposite directions to the position shown in Fig. 2, the usual weights acting in well 95 known manner to raise the tension-faller. As the latter rises the arm 8 is swung upward and the draft on the connector 6 swings the segment 4 upward until the lower end of its slot 5 engages the tail lug 20 and turns the pawl 16 on its pivot 17 to bring the pawl face 18 into locking engagement with the wheel flange 1. At the instant this locking engagement is effected the pawl, pawl-carrier, and segment 4 are positively locked 100 to the carriage wheel, and can only move as 105 a unit when the latter revolves. When locking is effected the rise of the tension-faller c is arrested with its wire c^x in engagement with the yarn Y , Fig. 2, at such an elevation 110 that the most of the slack yarn produced by backing off is taken up, but no strain is exerted upon the yarn. This is indicated by the slightly curved full line Y in Fig. 2, and the rise of the tension-faller to such point 115 is permitted by the lost-motion between the tail lug 17 and the lower end of the slot 5 of the segment. As soon as such lost-motion is taken up by the rise of the tension-faller, 120 acting through the connector 6, plus the slight angular movement of pawl 16 into locking position, the controlling means is locked to the carriage wheel and the rise of the tension-faller is positively arrested at 125 the desired point. It will be remembered 130

that during backing off the carriage is positively held from any movement, by usual mechanism forming no part of this invention, consequently no further rise of the tension-faller can take place until the carriage wheel A' revolves, and the wheel cannot revolve until the carriage is released and begins to move inward after backing off. When, therefore, the inward run of the carriage begins the wheel A' is revolved in the direction of the arrow 100, Figs. 2 and 6, and the several parts locked to the wheel turn with it as a unit, and the segmental member 4 as it rises slowly gives off the connector 6 gradually and the tension-faller is thereby permitted to rise at a slow rate of speed to gradually take up the slack yarn and finally exert full tension thereupon. The yarn now assumes substantially a straight line between the draft-rolls and the tension-faller wire c*, as indicated by the broken line Y', Fig. 2, the inward movement of the carriage having brought the parts movable therewith to the dotted line position. Thus no strain has been exerted upon the yarn by the tension-faller until after the carriage has moved inward subsequent to backing off, and there has been such a slow and gradual application of the strain up to the desired maximum that the possibility of yarn breakage due to the tension-faller is substantially eliminated. After the full strain due to the tension-faller has been applied to the yarn the winding operation acts through the yarn to depress the tension-faller and thereby the arm 8 is swung downward to slacken the connector 6, thus relieving the strain of the pawl governor or segment 4 upon the tail lug 20 and through the latter reducing the grip or locking pressure of the pawl 16 on the wheel flange 1, thereby unlocking the carriage wheel and the parts previously locked together. Further movement of said tension-faller as it is drawn down by the yarn allows the pawl-carrier 10 to gradually return by gravity to the limit of its downward movement, governed by engagement of the stop 13 with the wheel bracket A³, as in Figs. 1, 4 and 5, while the segment 4 returns to its normal position. During such return movement the pawl 16 is in light contact with the locking flange 1, due to the action of gravity on the parts while they are held in suspension by the connector 6, but the pressure of the pawl against the flange is then insufficient to prevent relative sliding movement of one over the other so that while the wheel continues to rotate as the carriage moves in the pawl will gradually slip back to normal position. The coöperation of the connector with the segmental face of the pawl governor provides for the necessary length of said connector available for the proper rise of the tension-faller before locking of the wheel is effected, for when the

fallers are locked together the slackened connector permits said pawl governor to move always to a definite position, with the acting end of the slot 5 at a fixed distance away from the tail lug 20. Thus the lost-motion to be taken up by the connector before the pawl locks and the tension-faller is arrested in its rise is always the same, and the tension-faller is arrested at the predetermined point. 75

The stop lug 12 of the pawl-carrier is a safety device and in practice is rarely called into action, its function being to prevent any angular movement of said pawl-carrier far enough to carry it above and beyond the journal A² of the carriage wheel. 80

From the foregoing description it will now be apparent that in our controlling means for the tension-faller all of the desirable features of the older devices referred to have been retained while the objectionable features have been eliminated. In our invention the controlling means is only brought into action by the backing off, hence it makes no difference whatever whether the carriage has moved in an inch or a foot prior to the backing off, and consequently the setting is automatic for all carriage positions. To provide for an automatic control where such control is most needed it will be obvious that such control, if by power, must be governed by some member or part of the general machine which is conveniently located and which can move or transmit motion at the proper time. In the present case the only parts or members in sufficient motion to govern the controlling means, and which are stopped during the backing off and started during the run in, are the carriage wheels, hence our controlling means for the tension-faller is governed by a carriage wheel. 95 100 105

We have disclosed herein one simple and practical embodiment of our invention, which fills all the requirements in actual practice, but various changes or modifications in details of construction and arrangement may be made by those skilled in the art without departing from the spirit and scope of our invention as set forth in the claims hereto annexed. 110 115

Having fully described our invention, what we claim as new and desire to secure by Letters Patent is:

1. In a mule, in combination, a carriage, a wheel therefor rotated by movement of the carriage, a tension-faller, and means to control the rise thereof and its coöperation with the yarn, said means including a pawl governor operatively connected with the tension-faller, and a pawl moved by said governor into locking engagement with the carriage wheel when the tension-faller has risen to a predetermined point, whereby subsequent rise of said faller to exert tension 120 125 130

upon the yarn is governed by rotative movement of the wheel when the carriage moves inward.

2. In a mule, winding and tension-fallers, 5 a carriage, a wheel therefor rotated by movement of the carriage, and an annular locking member rotatable with and concentric to said wheel, combined with a pawl-carrier fulcrumed co-axial with the wheel, a pawl 10 to coöperate with said locking member and cause the pawl and pawl-carrier to move bodily with the wheel, and connecting means between the tension-faller and the pawl, to move the latter into locking coöperation with said annular locking member by or through a predetermined rise of the tension-faller, whereby said tension-faller is arrested in its rise and held from further rise until the wheel is rotated by inward 15 movement of the carriage.

3. In a mule, in combination, a carriage, a rotatable governing member connected therewith and rotated only by the movement of the carriage, a tension-faller, controlling 20 means between said rotatable member and the faller and permanently connected with the latter, said means including a device rendered operative by initial rise of the tension-faller to lock together said means and 25 the rotatable member, to arrest rise of the faller until inward movement of the carriage rotates said governing member and thereby permits an additional and gradual 30 rise of the tension-faller.

35 4. In a mule, in combination, a carriage, a rotatable governing member connected therewith and rotated only by the movement of the carriage, a tension-faller, a connector interposed between said tension-faller and 40 the governing member and having a permanent connection with the former, and a normally inoperative device to positively connect said governing member and the connector when the latter is moved by the 45 initial rise of the tension-faller, whereby the rise of the latter is arrested while the carriage is at rest, subsequent inward movement of the carriage rotating the governing member to permit an additional but controlled rise of the tension-faller while the 50 connector and governor are positively connected.

5. The combination with a mule-carriage, its wheel rotated by movement of the carriage, an annular locking member mounted on the wheel, and winding and tension-fallers, of a pawl-carrier and a pawl governor, fulcrumed co-axially with the wheel, a pawl 55 movable by said governor into locking engagement with the annular member, to thereby lock the pawl-carrier and governor from movement relatively to the wheel, and a flexible connector between the governor and the tension-faller, initial rise of the 60 latter acting through the connector and 65

governor to cause locking engagement of the pawl and the annular member while the carriage is at rest, to thereby stop the rise of the tension-faller at a predetermined point, subsequent rotation of the carriage 70 wheel and annular locking member letting off the connector to permit a further but controlled and gradual rise of the tension-faller.

6. In a mule, in combination, a carriage, a 75 wheel therefor rotated by movement of the carriage, a tension-faller, and normally inactive means rendered active by the initial rise of the tension-faller to control the same thereafter in its coöperation with the yarn, 80 said means when active being governed as to its operation by or through the carriage wheel.

7. In a mule, in combination, a carriage 85 and its wheel rotated by movement of the carriage, winding and tension-fallers, and means governed by rotation of said wheel after backing off to control the rise of the tension-faller and cause the same to exert tension upon the yarn gradually. 90

8. In a mule, in combination, a carriage, a member thereon rotated only by movement of the carriage, a tension-faller, and a device co-acting with said rotatable member to temporarily arrest the tension-faller when 95 passing into contact with the yarn at the beginning of the winding movement of the mule.

9. The combination with a mule-carriage, 100 an annular member rotated only by movement of the carriage, and a tension-faller, of normally inactive means between said member and the tension-faller to control the rise and coöperation of the latter with the yarn, said means including a device moved 105 into locking engagement with said annular member by or through initial rise of the tension-faller when the carriage is at rest, to stop the said faller before it has exerted tension on the yarn, subsequent rotation of 110 the annular member by movement of the carriage acting through the means locked thereto to permit a gradual and positively controlled rise of the tension-faller to exert tension upon the yarn. 115

10. In a mule, in combination, winding and tension-fallers, a carriage, a wheel therefor rotatable by movement of the carriage and having an annular locking flange, a pawl-carrier and a pawl governor, fulcrumed co-axially with said wheel, a pawl 120 on the carrier, movable with it and also relatively thereto into engagement with the locking flange, to thereby lock together said pawl-carrier and the wheel, and a connection between the tension-faller and pawl governor, initial rise of the tension-faller 125 acting through said connection and the governor to move the pawl into locking position while the carriage is at rest, to thereby ar- 130

rest the rise of the said faller until movement of the carriage rotates the wheel and effects movement therewith of the pawl-carrier, pawl, and governor to let off the connection and permit further gradual rise of the tension-faller.

11. In a mule, in combination, winding and tension-fallers, a carriage, a wheel therefor rotatable by movement of the carriage 10 and having an annular locking flange, a pawl-carrier fulcrumed co-axially with the wheel, a pawl on said carrier, movable into engagement with the annular flange to lock together the wheel and pawl-carrier, and 15 means between the tension-faller and the pawl to move the latter into locking position by or through rise of the tension-faller to a predetermined point when the carriage is at rest, such locking engagement of the pawl 20 and flange arresting the rise of the tension-faller until subsequent movement of the carriage rotates the wheel and permits a further gradual rise of the tension-faller.

12. In a mule, in combination, a carriage, 25 a member thereon rotated only by movement of the carriage, winding and tension-fallers, and normally inactive means connected with the tension-faller and operatively connected with said rotatable member by or through rise of the tension-faller when the carriage is at rest, to arrest the 30 rise of such faller before strain is exerted upon the yarn, inward movement of the carriage after backing off rotating said rota-

table member to act through said means and 35 permit a further and positively controlled rise of the tension-faller to exert tension upon the yarn.

13. The combination with a mule-carriage, 40 a governing member rotated only by movement of said carriage, and winding and tension-fallers, of means connected with and to control the rise of the tension-faller, including a member brought automatically into operative engagement with said governing 45 member by a predetermined rise of the tension-faller when the carriage is at rest, to arrest such rise before tension is exerted upon the yarn, rotation of the governing member by inward movement of the carriage 50 acting through said controlling means to permit a further and positively controlled rise of the tension-faller to subject the yarn to tension, the member of the controlling means and said governing means 55 being disengaged automatically by or through the descent of the tension-faller when it is depressed by the yarn, and means to stop such member in normal position after its disengagement from the governing means. 60

In testimony whereof, we have signed our names to this specification, in the presence of two subscribing witnesses.
